UNITED STATES PATENT OFFICE.

GEORGE PFEIFFER, OF PROVIDENCE, RHODE ISLAND, ASSIGNOR TO CROMPTON & KNOWLES LOOM WORKS, OF WORCESTER, MASSACHUSETTS, A CORPORATION OF MASSACHUSETTS.

CENTER STOP-MOTION.

1,270,865.

Specification of Letters Patent.

Patented July 2, 1918.

Application filed December 26, 1917. Serial No. 208,744.

To all whom it may concern:

Be it known that I, GEORGE PFEIFFER, a citizen of the United States, residing at Providence, in the county of Providence and State of Rhode Island, have invented 5 a new and useful Center Stop-Motion, of which the following is a specification.

This invention relates to a center stop motion for looms, and particularly to improved devices for permitting relative adjustment between the several parts thereof and for securing said parts in adjusted position.

In the type of stop motion to which my 15 invention is applied, the filling fork is mounted on the lay near the center of the warp, and the actuating element or dagger is mounted near the end of the lay at the side of the loom. A longitudinally extended 20 connecting rod extends from the filling fork to the crank disk by which the dagger is positioned.

It is the object of my invention to provide improved devices for securing the crank disk 25 to the connecting rod, said devices permitting relative angular adjustment of said disk and rod, and also longitudinally positioning the crank disk in its bearing.

With this general object in view, my invention relates to certain arrangements and combinations of parts hereinafter described and more particularly pointed out in the appended claims.

A preferred form of my invention is 35 shown in the drawing, in which—

Figure 1 is a side elevation of a center stop motion;

Fig. 2 is a top plan view of said stop motion;

Fig. 3 is a vertical sectional detail view taken along the line 3—3 in Fig. 1, and

Fig. 4 is a transverse sectional view taken along the line 4—4 in Fig. 3.

I have shown my invention applied to a 45 common form of stop motion comprising a filling fork 10 mounted at one end of a connecting rod 11 which extends along the front side of the lay 12, one end of said rod being supported near the center of the loom 50 in a bearing 13. At the side of the loom a dagger 14 is pivoted at 15 to a bracket 16 on the lay 12, said dagger being designed to cooperate with a notched collar 17 on a rod 18 through which the usual shifter is controlled. The dagger 14 is connected through

a link 19 to a crank disk 20. All of the parts thus far described are of the usual form and form no part of my invention. For a more complete description of these parts reference is made to the patent to McGuiness, No. 60 1,223,708, issued April 24, 1917.

My present invention relates specifically to improvements in the means for connecting the disk 20 to the rod 11. For the purpose of such connection the disk 20 is provided 65 with a hollow split hub or sleeve 21 extending through a bearing 22 mounted on the lay 12. The end of the rod 11 fits loosely within the hollow hub 21. A collar 23 is secured to the extended inner end of the hub 70 21, and a set screw 24 in the collar 23 provides means for clamping the collar securely on the hub 21, and for thus contracting the hub or sleeve upon the rod 11. The collar 23 when thus secured also co-operates with the 75 disk 20 to longitudinally position the hub 21 in the bearing 22. By loosening the screw 24 any desired angular adjustment between the disk 20 and the rod 11 may be readily made.

By this simple arrangement I am able to secure accurate angular adjustment of the parts 11 and 20 and to hold the parts firmly in adjusted position. At the same time I also position the disk 20 longitudinally relatively to its bearing 22. The parts involved are of simple construction and low cost of manufacture, and the adjustment when once secured is rigidly retained.

Having thus described my invention, it 90 will be evident to those skilled in the art that changes and modifications can be made therein within the scope of my invention as set forth in the claims and I do not wish to be otherwise limited to the details herein disclosed, but what I claim is:—

1. A center stop motion comprising a filling fork, a dagger, a crank disk, a bearing for said disk, a link connecting said disk to said dagger, and connections between said disk and said filling fork, said connections including a longitudinally extended rod on which said filling fork is mounted, and means to firmly secure said rod and disk together, said means permitting relative angular adjustment of said rod and disk but preventing longitudinal movement of said disk relatively to said bearing.

2. A center stop motion comprising a filling fork, a dagger, a crank disk, a bearing 110

for said disk, a link connecting said disk to said dagger, and connections between said disk and said filling fork, said connections including a split hollow hub for said disk 5 extending through and beyond said bearing, a longitudinally extended rod to which said filling fork is secured, the end of said rod fitting loosely in said hollow hub, a collar

on the extension of said hub adjacent said bearing, and means to secure said collar 10 on said hub and to simultaneously bind said hub on said rod.

In testimony whereof, I have hereunto affixed my signature.

GEORGE PFEIFFER.
